No. 895,588.

PATENTED AUG. 11, 1908.

E. A. RICHARDSON.
COIN CONTROLLED LOCK.
APPLICATION FILED AUG. 14, 1907.

UNITED STATES PATENT OFFICE.

EDWIN A. RICHARDSON, OF WORCESTER, MASSACHUSETTS.

COIN-CONTROLLED LOCK.

No. 895,588.

Specification of Letters Patent.

Patented Aug. 11, 1908.

Application filed August 14, 1907. Serial No. 388,442.

To all whom it may concern:

Be it known that I, EDWIN A. RICHARDSON, a citizen of the United States, residing at Worcester, in the county of Worcester and 5 State of Massachusetts, have invented a new and useful Coin-Controlled Lock, of which the following is a specification.

The object of this invention is to provide a new and improved locking mechanism which 10 will be controlled by a coin so that when the coin is inserted, the lock can be operated and the key withdrawn, and so that when the key is again inserted and the lock unlocked, the key will be held in the lock and cannot be 15 again removed until a new coin is inserted.

The mechanism can be used advantageously in many locations, as for example, in umbrella racks, whereby by inserting a nickel or other coin, the umbrella can be 20 locked up, the key carried away and when the lock is unlocked to take out the umbrella, the key is locked in the device.

Enough of the essential features of the mechanism are shown in the accompanying 25 drawing forming part of this specification to enable those skilled in the art to practice the same.

Referring to said drawing, Figure 1 is a front elevation partly in section showing the 30 lock unlocked. Fig. 2 is a front elevation with the mechanism locked. Fig. 3 is a sectional plan view. Fig. 4 is a plan view of the two operating disks. Fig. 5 is a front view of the loose disk. Fig. 6 is a perspective 35 view of the lock-operating disk. Fig. 7 is a sectional elevation illustrating the operation when a penny is inserted.

The operation of the mechanism will be best understood by a detailed description 40 thereof.

Referring to the drawing and in detail, 10 designates a box or casing which is turned or bored out to have a circular hole. A back plate 11 and a front plate 12 are secured 45 thereto in any suitable manner. The front plate 12 is provided with one or more of the usual key guiding disks 13 so that only one particular key can be inserted in the lock. A loose disk 14 is journaled or fitted in the 50 box or casing. This loose disk is provided with notches 15—15, the bottoms of which are inclined, as shown at 151 in Fig. 7, for a purpose hereinafter described. The disk 14 is formed with a central hole 150 and is provided with lugs 152 which leave a suitable 55 slot 153 so that when the right key K is in-

serted therein, the loose disk 14 can be turned by the key.

16 designates a lock-operating disk which is also fitted in the casing 10. This lock-operating disk has suitable notches 17—17. 60

The box or casing is provided with a coin-receiving chute C and a coin-outlet O. The lock-operating disk always stands so that one of its notches 17 comes in registration with the chute C and one of its notches in registration with the outlet O, when the parts are in 65 unlocked position as shown in Fig. 1. The lock-operating disk 16 is cut away and a pawl spring 18 is inserted therein. 70

The casing 10 is provided with suitable notches 19—19 so arranged that the lock-operating disk can only be turned in one direction and that, the direction indicated by the arrows in Figs. 1 and 2. The lock-operating 75 disk 16 is provided with two bolt operating pins 20—20.

21 designates the sliding bolt which works on a guide pin 22. The bolt 21 is provided with an operating arm 23 against which the 80 pins 20—20 bear and with a locking notch 230. The bolt 21 is normally held in retracted position by a spring 24 fitted on an arm 25, the ends of the spring being secured to the casing and to the bolt 21. 85

The front plate 12 is provided with a key slot 26 which in the particular arrangement illustrated, stands in horizontal position. The lock-operating disk 16 is provided with a slot 27 through which the key is inserted. 90 The slot 26 registers with the slot 27 when the bolt is in locked position, and stands at right-angles thereto when the bolt is in retracted position.

The key K is provided with key-retaining 95 arms 28 which can pass through the slot 27 in the lock-operating disk when the slots 26 and 27 are in registration. The key cannot be inserted in between the lugs 150 to operate the loose disk unless the arms 28 thereof 100 pass through the lock-operating disk 16.

The device as shown is arranged to be operated by a nickel or five-cent piece. The lock is shown in its normal or unlocked position with the key locked therein, in Figs. 1 105 and 3. When the nickel is inserted in the chute C, the key K is turned to bring the notches 15 of the loose disk 14 into registration with the slots 17 of the lock-operating disk 16, if that condition does not exist. 110 When these notches are brought into registration, the nickel will drop down into the

disks 14—16, locking the same together as shown in Fig. 4. The key is now given a quarter turn which will bring the slot 27 into registration with the key slot 26 whereby the 5 key can be withdrawn leaving the bolt out, as shown in Fig. 2. As this action takes place, the pin 20 will run up on the arm 23 on the bolt 21 and will snap into the notch 230. In this position of the parts, the operating 10 disk can only be turned in a direction indicated by the arrows and the spring 24 cannot pull the bolt back.

When it is desired to unlock the device, the key is inserted and given another quarter 15 turn in the same direction. This will move the operating pin 20 which engages the bolt 21 clear of the operating arm 23 when the bolt 21 will fly back under the tension of the spring 24, unlocking the lock. After this 20 quarter turn, the parts will be brought back to the position shown in Fig. 1, the pawl 18 engaging one of the notches 19—19. As this takes place, the coin will come opposite the outlet chute O and will drop out of the disks 25 14—16 so that any further rotation of the key will not operate the disk 16. This will leave the disk 16 in normal position with the key K locked in the device from which it cannot be removed until a nickel is again inserted. 30 If a penny is dropped into the chute, when the disks 14 and 16 come into registration, the same will roll so as to come entirely within the disk 14, as shown in Fig. 7, the disk 14 being made the width of a penny for this purpose and the disks 14 and 16 together being made of a width a little larger than a nickel so that a nickel will lock the parts together. By this mechanism a simple and efficient device is provided for the purpose stated. 35 Having thus fully described my invention, 40 what I claim and desire to secure by Letters-Patent is:—

1. In a device of the class described, the combination of a loose disk adapted to turn 45 with a key, a locking bolt, and a disk having means for operating said bolt and having a slot in which the key will freely turn, said disks having notches in which a coin or the like may be lodged to lock them together so 50 that both of the disks will turn with the key.

2. In a device of the class described, the combination with a key of a loose disk through which the key is adapted to pass and having means by which it is caused to turn 55 with the key, a locking bolt, and a disk having means for operating said bolt and having a slot in which said key freely turns, said disks having notches in which a coin or the like may be lodged to lock them together so 60 that the turning of the key will turn both disks and operate the lock.

3. In a device of the class described, the combination of a loose disk adapted to turn with a key, a locking bolt, a second disk hav-

ing means for operating said bolt and having a slot therethrough in which the key freely turns, said disks having notches adapted to come into registration whereby the disks may be locked together by a coin along said notches, and means for preventing the key 70 from being withdrawn except when the bolt is in locking position.

4. In a device of the class described, the combination of a notched loose disk which can be turned by the key, a notched bolt operating disk, which two disks can be locked together by a coin, a slot in the lock-operating disk which registers with the key hole, and a key provided with a retaining arm projecting beyond said lock-operating disk whereby the 80 key can only be withdrawn when the lock is locked.

5. In a device of the class described, the combination of a casing having a cylindrical passage therethrough, a loose disk fitted in 85 said passage, and a lock-operating disk in said passage, said disks having means for receiving a coin so that the coin will lock said disks together, a front plate having a key-hole, the walls of said key-hole constituting 90 means for preventing the key from being withdrawn except when the bolt is in locking position, whereby when the key is inserted the same will be locked in the device when the bolt is unlocked.

6. In a device of the class described, the combination of a casing, a loose disk fitted therein, a lock-operating disk fitted therein, said disks being notched to receive a coin, a front plate having a key hole, and a slot cut 100 in said lock-operating disk, the parts being arranged so that the key can only be withdrawn when the bolt is in locking position and so that when the key is inserted the same will be locked in the device when the bolt is 105 unlocked.

7. In a device of the class described, the combination of a casing, a loose notched disk and a notched lock-operating disk fitted therein, the lock-operating disk having a slot, 110 a cover plate having a key slot, and lugs arranged in the loose disk whereby the key will be locked in the device at all times except when the bolt is in locking position.

8. In a device of the class described, the 115 combination of a casing, a loose disk, and a lock-operating disk therein adapted to be locked together by a coin or the like, the lock-operating disk having a slot, and a cover plate having a key slot, said loose disk 120 having means for preventing the key being inserted or removed except when the bolt is in locking position.

9. In a device of the class described, the combination of a casing having a cylindrical passage therethrough, a loose notched disk, and a notched lock-operating disk fitted 125 therein, and a pawl carried by the lock-oper-

ating disk, said casing having notches in the walls thereof for preventing the lock-operating disk from being turned in one direction.

10. In a device of the class described, the combination of a loose notched disk and a notched lock-operating disk, a sliding bolt having a projecting arm, pins carried by the lock-operating disk for engaging said arm, means whereby the lock-operating disk can only be turned in one direction, a coin inlet

chute, and a coin outlet, the parts being arranged so that the coin will lock the two disks together.

In testimony whereof I have hereunto set my hand, in the presence of two subscribing 15 witnesses.

EDWIN A. RICHARDSON.
